OTHER PUBLICATIONS

An Office Action mailed by China National Intellectual Property Administration dated Feb. 5, 2021, which corresponds to Chinese Design Application No. 202030557855.0 and is related to Design U.S. Appl. No. 29/753,311; with English language translation.

Primary Examiner — Joseph Kukella*Assistant Examiner* — Heather A Wencel(74) *Attorney, Agent, or Firm* — Studebaker & Brackett
PC(57) **CLAIM**

The ornamental design for an operating panel for elevator, as shown and described.

DESCRIPTION

FIG. 1 is a perspective view of an operating panel for elevator, showing our new design;

FIG. 2 is a front view thereof;

FIG. 3 is a rear view thereof;

FIG. 4 is a right side view thereof;

FIG. 5 is a top view thereof;

FIG. 6 is a bottom view thereof;

FIG. 7 is an enlarged cross-sectional view thereof; taken along line 7-7 of FIG. 2, with the internal system omitted; and,

FIG. 8 is a reference view showing the state in use.
